UNITED STATES PATENT OFFICE.

GILBERT W. ALLEN AND CHARLES W. ALLEN, OF SYRACUSE, NEW YORK.

DISINFECTING DEVICE.

No. 920,711.

Specification of Letters Patent.

Patented May 4, 1909.

Application filed October 20, 1908. Serial No. 458,666.

To all whom it may concern:

Be it known that we, GILBERT W. ALLEN and CHARLES W. ALLEN, citizens of the United States, residing at Syracuse, in the county of Onondaga and State of New York, have invented certain new and useful Improvements in Disinfecting Devices; and we do hereby declare the following to be a full, clear, and exact description of the invention, such as will enable others skilled in the art to which it appertains to make and use the same.

Our invention relates to new and useful improvements in disinfecting devices and more particularly to that class adapted to be used in connection with garbage cans, etc., and our object is to provide receptacles within the garbage cans for retaining the disinfectant and a further object is to provide a suitable cover for the disinfectant chambers, which will permit the disinfectant or fumes therefrom to pass into the garbage can and destroy vermin, etc., which might accumulate in the garbage and likewise destroy the odors from the garbage.

Other objects and advantages will be hereinafter referred to and more particularly pointed out in the claim.

In the accompanying drawings which are made a part of this application, Figure 1 is a vertical sectional view through a garbage can, showing our improved disinfectant holding devices in position therein, and, Fig. 2 is a sectional view as seen on line 2—2, Fig. 1.

Referring to the drawings in which similar reference numerals designate corresponding parts throughout the several views, 1 indicates a garbage can which may be constructed in the usual or any preferred manner and is provided with a cover 2, which is adapted to close the upper end of the can.

In order to retain a suitable disinfectant within the can and in such manner that the odors from the disinfectant will commingle with the odors from the garbage, we have provided pockets 3, which are preferably

oblong and open at their upper ends, while their lower ends are curved as at 4, said pockets being secured at suitable points on the inner wall of the can and at a point adjacent the upper end of the can.

The pockets 3 are provided with closure caps 5, said caps being provided with depending flanges 6, which are adapted to enter the open ends of the pockets and by forming the flanges of such size as to closely fit within the pockets, the caps will be retained in position when the can is tilted to remove the contents thereof. The caps 5 are provided with a plurality of perforations 7, whereby the odors from the disinfectant may readily leave the pockets and enter the body of the can and will also permit a quantity of the disinfectant to leave the pockets and commingle with the garbage when the can is being emptied.

By curving the lower ends of the pockets 3, as shown, the garbage, when being removed from the can, will readily pass by the pockets without interrupting the movement of the garbage and by placing the pockets adjacent the upper end of the can, said can may be filled with garbage to a point adjacent its upper end without interfering with the action of the disinfectant.

What we claim is:

A device of the character described, comprising a garbage can and a pocket applied laterally to the inner surface of said can and of approximately oblong cross section, said pocket having its bottom curved downwardly toward the side of said can, and a perforated cover for said pocket, said cover having a flange depending from its inner surface and engaging the sides of said pocket.

In testimony whereof we have signed our names to this specification in the presence of two subscribing witnesses.

GILBERT W. ALLEN.
CHARLES W. ALLEN.
